CLAIM

The ornamental design for a strap for speaker as shown and described.

DESCRIPTION

1.1: Perspective

1.2: Front

1.3: Left

1.4: Right

1.5: Top

1.6: Bottom

1.7: Reference view

1.8: Reference view

1.9: Reference view

The back view is omitted because it is a mirror image of the front view; reproduction **1.7** is a reference view showing the state in which the claimed design is folded and forms no part of the claimed design; reproductions **1.8** and **1.9** are reference views showing the state in which the claimed design is coupled with the speaker and form no part of the claimed design; the broken lines in reproductions **1.8** and **1.9** form no part of the claimed design; all other broken lines indicate portions of the article that form no part of the claimed design.
